UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

MOORING DEVICE.

Application filed February 26, 1925. Serial No. 11,684.

This invention relates to devices for mooring boats to bridges such as that illustrated in Reissue Patent No. 14,813, to Du Bosque, granted June 5, 1917.

The invention relates more particularly to the connection or hitch between the lifting and counterbalancing mechanism and the bridge and boat.

The invention has for its salient object to provide a practical and simplified connection or hitch between the lifting or counterweighting mechanism and the boat and bridge whereby the bridge and boat will be securely connected together.

Another object of the invention is to provide a hitch that can be readily attached to and detached from the bridge and boat.

Further objects of the invention will appear from the following specification taken in connection with the drawings, which form a part of this application, and in which—

Fig. 1 is an elevational view somewhat diagrammatic showing the lifting and counterbalancing mechanism and the connection between the bridge and boat.

Fig. 2 is a side elevational view of the connection or hitch shown in Fig. 1.

Fig. 3 is a view similar to Fig. 2 but illustrating a slightly modified form of the invention.

Fig. 4 is a view similar to Figs. 2 and 3, but illustrates another form of the invention.

Fig. 5 is a sectional elevation on an enlarged scale illustrating the swivel connection between the hitch and the bridge, and

Fig. 6 is a view similar to Fig. 2, but illustrates a further form of the invention.

The invention briefly described consists of the combination of a boat, and a bridge preferably hinged and over which passengers and freight can pass to and from the boat, and lifting mechanism so connected to the bridge and to the boat that the bridge and boat will be firmly anchored together. The hitch or connection between the lifting mechanism and the boat is so constructed that the lifting force is divided into horizontal and vertical components whereby the boat and bridge will be drawn together and whereby the interengaging parts of the

bridge and boat will be vertically supported. Further details of the invention will appear from the following description.

In the embodiment of the invention illustrated in Figs. 1 and 2, one end 10 of a bridge is shown, the bridge preferably being hinged in the usual manner. Stationary parts of the dock are shown at 11 and cross beams 12 extend between upright portions 13 of the dock. The greater portion of the weight of the bridge is balanced by counterweights 14 which are connected to the outer or free end of the bridge by chains or cables 15 which in turn pass over sheaves 16 mounted on the beams 12. The counterweights 14 exert a lifting force of constant magnitude on the bridge.

In order to exert the necessary lifting effect on the bridge and boat to securely anchor these parts together, an auxiliary weight 20 is supported on cables 21. A yoke 22 is secured to the cables 21 and supports a plurality of sheaves 23 and the weight 20 is also connected to a frame 24 having a plurality of sheaves 25 secured therein. The sheaves 23 and 25 correspond in number and a cable 30 is secured at one end 31 to the yoke 22 and passes around the sheaves 25 and 23, the opposite end of the cable being connected to a drum 26 which is shown as driven by a motor 27. A platform 28 supported by springs 29 is disposed beneath the weight 20 and is adapted to support the weight when the cable 30 is sufficiently slack to permit the weight to rest thereon.

Each of the cables 21 passes over sheaves 35 and has its free end connected to a link 36.

In the embodiment of the invention particularly illustrated in Figs. 1, 2 and 5, the free end 37 of the bridge has swiveled therein an anchor bolt 38, the bolt being mounted in bearings 39. The bolt 38 has lugs 40 extending upwardly therefrom and a lever 41 is pivoted to the lugs 40. An eye 42 is also pivotally connected to the lugs 40 and is connected by a chain 43 to a link comprising a pair of sections 44 and 45 adjustably connected by a turnbuckle 46. The upper end of the section 45 of the link is connected at 47 to the link 36.

The lever 41 is connected intermediate its ends at 50 to a chain 51 which in turn is connected to a hook 52 carried by the boat 53.

The end of the boat adjacent the bridge 5 may be undercut as shown at 54 to receive an overhanging portion 55 of the bridge. The free end of the lever 41 is connected by a link 56 to the link 36.

In operation, the cable 30 is slackened to a sufficient extent to allow the overhanging portion 55 of the bridge to seat in the undercut portion 54 of the boat. The chain 51 is then passed over the hook 52 and the cable 30 is tightened thereby lifting weight 20 and 15 tightening the cables 21. As the cables 21 are drawn taut, the lever 41 will exert a lifting and drawing force on the boat, thereby drawing the boat into engagement with the end of the bridge and securely locking the 20 boat and bridge together. In other words, the force exerted on the cable 21 will be divided into vertical and horizontal components.

In the embodiment of the invention illustrated in Fig. 3, the hitch illustrated is designed on the same principle as that shown in Fig. 2. In this form of the invention, however, the lever 41 is connected by a link 60 to the hook 52 and the swivel bolt 48 is 25 connected by a link 61 to a link 62. A turnbuckle 63 adjustably connects one end of the link 62 to the pivotal connection 64 of the link 61.

In the embodiment of the invention shown in Fig. 4, the cable 21 is connected at 70 to the free end of the lever 41 and there is no direct connection between the cable and the bridge. In this case, the bridge is raised and lowered through the intervention of the 35 connection of lever 41 to the swivel bolt 38 carried by the bridge and after the bridge rests on the end of the boat, the cable is slackened to permit the link 60 to be secured over the hook 52.

In Fig. 6, a simpler form of the invention is shown in which the cable 21 has secured to its free end an eye 75 which in turn is connected to an eye 76 on the bridge by a cable or chain 77 and to the hook 52 on the 50 boat by a cable or chain 78. In this form of the invention, the vertical lifting force on the cable 21 is divided into vertical and horizontal components tending to vertically support the bridge and boat and to draw 55 these parts into firm engagement with each other.

From the foregoing description it will be seen that simple and practical means has been provided for firmly and securely anchoring or mooring a boat such as a ferry boat to a bridge.

Although certain specific embodiments of the invention have been particularly shown and described, it will be understood that the 60 invention is capable of modification and that

changes in the construction and in the arrangement of the various cooperating parts may be made without departing from the spirit or scope of the invention, as expressed in the following claims.

What I claim is:—

1. In combination, a bridge, a boat to be moored thereto, lifting mechanism, a connection between said lifting mechanism and the bridge directly secured to a fixed point 70 on the bridge and a connection between the lifting mechanism and said boat affixed to the boat at a point spaced from the point of connection on the bridge, said connection to the boat having vertical and horizontal 75 components.

2. In combination, a bridge, a boat to be moored thereto, lifting mechanism, and a lever pivotally connected to said bridge at a fixed point thereon, a connection between 80 the lever and the boat and another connection between the lever and the lifting mechanism.

3. In combination, a bridge, a boat to be moored thereto, lifting mechanism, and a lever pivotally connected at one end to said bridge at a fixed point thereon, a connection 85 between the other end of the lever and the lifting mechanism and another connection from a point intermediate the ends of said lever to a point on the boat spaced from said pivotal connection on the bridge.

4. In combination, a bridge, a swivel on the bridge, a boat to be moored to said bridge, lifting mechanism, and a lever pivotally connected to said swivel and connected at points spaced from the swivel to 90 said lifting mechanism and to said boat.

5. In combination, a bridge, a boat to be moored thereto, lifting mechanism, and a lever pivotally connected at one end to said bridge at a fixed point thereon, a connection 95 between the other end of the lever and the lifting mechanism and another connection from a point intermediate the ends of said lever to a point on the boat spaced from said pivotal connection on the bridge, and a connection between said lifting mechanism and the bridge.

6. In combination, a bridge, a boat to be 110 moored thereto, lifting mechanism, and a lever pivotally connected at one end to said bridge at a fixed point thereon, a connection between the other end of the lever and the lifting mechanism and another connection 115 from a point intermediate the ends of said lever to a point on the boat spaced from said pivotal connection on the bridge, and an adjustable connection between said lifting mechanism and the bridge.

7. In combination, a bridge, a swivel on the bridge, a boat to be moored to said bridge, lifting mechanism, and a lever pivotally connected to said swivel and connected at points spaced from the swivel to said 120

lifting mechanism and to said boat, and an adjustable connection between said lifting mechanism and the bridge.

8. In combination, a bridge having an overhanging portion, a boat having a portion to receive the overhanging portion of the bridge, lifting mechanism, a connection between said lifting mechanism and the bridge directly secured to a fixed point on the bridge and a connection between the lifting mechanism and said boat, affixed to the boat at a point spaced from the point of connection on the bridge, said connection to the boat having vertical and horizontal components.

9. In combination, a bridge having an overhanging portion, a boat to be moored thereto having a recessed portion to receive the overhanging portion of the bridge, lifting mechanism, and a lever pivotally connected at one end to said bridge at a fixed point thereon, a connection between the

other end of the lever and the lifting mechanism and another connection from a point intermediate the ends of said lever to a point on the boat spaced from said pivotal connection on the bridge, and a connection between said lifting mechanism and the bridge.

10. In combination, a bridge having an overhanging portion, a swivel on the bridge, a boat to be moored to said bridge having a recessed portion to receive the overhanging portion of the bridge, lifting mechanism, and a lever pivotally connected to said swivel and connected at points spaced from the swivel to said lifting mechanism and to said boat, and an adjustable connection between said lifting mechanism and the bridge.

In witness whereof, I have hereunto set my hand this 20th day of February, 1925.

CHARLES C. TOMKINSON.
